UNITED STATES PATENT OFFICE.

CARL F. BUSCHNER, OF NEW YORK, N. Y.

DESIGN FOR FRINGE.

SPECIFICATION forming part of Design No. 26,918, dated April 13, 1897.

Application filed February 3, 1897. Serial No. 621,892. Term of patent 7 years.

To all whom it may concern:

Be it known that I, CARL F. BUSCHNER, a citizen of the United States, residing at New York city, in the county of New York and State of New York, have invented and produced a new and original Design for Fringe, of which the following is a specification, reference being had to the accompanying drawings, showing a part thereof.

10 Figure 1 represents a side view of my newly-designed fringe. Fig. 2 is a cross-section thereof.

The leading feature of my design consists of a fringe having a continuous tubular edge, 15 a head beneath such edge, and a brush beneath the head.

The letters *a* represent a number of equiformed loops placed side by side and forming a continuous tube, which constitutes the upper edge of the fringe.

Below the tubular edge *a* there is formed the twilled head *b*, and below the head *b* is formed the brush *c*.

What I claim is—

The design for fringe, substantially as herein shown and described.

CARL F. BUSCHNER.
